BOTTOM RING FOR HOT TOPS

Walter M. Charman, Cleveland Heights, Ohio

Application January 28, 1931, Serial No. 511,733

12 Claims. (Cl. 22—147)

This invention relates to bottom rings for hot tops, and has reference particularly to improvements in non-floating hot tops of that class in which metal casings are employed. Such hot tops rest upon the ingot mold during the pouring operation, and may or may not be anchored to the mold. The joint between the casing and the hot top must be relatively tight in order to prevent molten metal from entering it. Consequently part or all of the upper surface of the ingot mold is usually machined, and the lower end surface of the hot top is likewise machined, for the purpose of truing up these two surfaces to meet throughout their extent. In spite of these precautions molten metal sometimes finds its way into the joint, solidifies and then tends to "hang up" the ingot thereby interfering with its natural shrinkage during cooling, and serves to weld the two surfaces together.

A portion of the lower end of such a casing is also necessarily exposed to the molten metal poured through the hot top. After a series of operations this exposed metal is adversely affected and, in the course of time, becomes pitted and cracked to such an extent that the protuberances and fins on the ingot resulting from the flow of metal into such inequalities, interfere considerably with the operation of stripping the hot top from the ingot and finally make a new casing necessary. By the use of my invention however the casing proper has an indefinite life, and the part which is to be replaced is relatively small and of relatively low cost.

One of the objects of the invention therefore is the provision in a hot top of the non-floating type of means for protecting the lower end of the hot top casing, which means shall be removable and replaceable when occasion demands.

Another object is the provision of securing means for the removable section adapted to fail when subjected to unusual strains such as are exerted in separating the hot top from the mold when these two parts tend to stick together on account of the welding action of molten metal above explained, or in stripping the hot top from the ingot when adherence between them becomes strong due to the metal entering the inequalities of the bottom ring.

Still another object of the invention is the provision of a yieldable pad or gasket between the hot top casing and ingot mold in order to effect a good seal for this joint, and preferably an extension of this pad or gasket inwardly and upwardly to constitute a lining for a portion of the hot top as a protection for the inner wall thereof.

Other objects and features of novelty will appear as I proceed with the description of those embodiments of the invention which, for the purposes of the present application, I have illustrated in the accompanying drawing, in which

Figure 1 is a vertical sectional view of a hot top and a fragment of the upper end of an ingot mold in connection with which my invention is employed.

Fig. 2 is a similar view with the pad and lining element added.

Fig. 3 is a fragmental plan view of one corner of the bottom ring.

Fig. 4 is a cross sectional view taken substantially on the line 4—4 of Fig. 3, and

Fig. 5 is a detail elevational view of a fastening which may be employed for holding the bottom ring to the casing.

In the drawing a fragment of an ingot mold is illustrated at 10, having a rabbet 11 with a trued upper surface formed preferably by machining. The mold may have a cavity of any desired cross sectional form, as for instance approximately rectangular, approximately round, fluted or the like.

The casing of the hot top shown at 12 is of iron cast in one or a plurality of parts. If the casing is not made in one piece its parts are bolted or otherwise secured together in a more or less permanent fashion. The casing comprises a lower inwardly extending ledge 13 running preferably entirely around the casing, and may have also an inwardly extending upper ledge 14. The inner wall of the casing between these two ledges is covered with a heat insulating lining which, in the present instance, takes the form of two tiers of refractory blocks 15 and 16. The lower tier is supported wholly or partially upon the ledge 13.

Heretofore it has been the practice to machine the lower end surface of the hot top casing, corresponding to the lower surface of ledge 13 of the present disclosure, and let it rest upon the machined surface of the ingot. In accordance with my invention however the lower end of the casing proper may or may not be machined, for it is covered by an auxiliary ledge member 17 which is interposed between the mold and the casing 12. This auxiliary member extends under the ledge 13 and protects the entire lower and inner surfaces thereof. It has an inner rim portion which stands flush with the upper surface of ledge 13, and may assist that ledge in the support of the blocks 15. This inner rim portion also stands flush or nearly flush with the inner sur-

face of lining blocks 15. The ledge member 17 may be machined on its lower surface, and on account of its relatively small size the machining may be more easily effected than could be the machining of the casing proper. The auxiliary ledge is preferably made as an annulus in a single piece, but obviously may be constructed of a plurality of pieces if desired. It is detachably mounted upon the casing by suitable means such as will hereinafter be described in connection with the form of the invention illustrated in Fig. 2.

In the latter figure the annular auxiliary ledge member 17 is the same as in Fig. 1, except that it is provided with a series of holes for the reception of plugs 18, made preferably of wood. These plugs are renewed after each heat and are put in with a driving fit. After they are in place a non-inflammable annular gasket and lining member 19, made preferably although not necessarily in one piece, and formed to fit snugly, is pushed into place covering the lower end surface of the ring 17 and extending over its inner surface exposed to the molten metal and up over the joint between the ring and the blocks 15. Nails 20 with large heads are then driven through the member 19 into the plugs 18, thereby securing the member 19 to the hot top. When the molten metal is poured the plugs 18 become charred and lose their grip upon the nails 20, so that when the hot top is stripped from the ingot the member 19 remains upon the ingot, affording an excellent parting surface. Other means, adapted to fail when the hot top is stripped from the mold, 35 may of course be substituted for that described without departing from the invention, or the member 19 may be held in place by friction alone.

By the term "non-inflammable" as herein applied to the member 19 I intend to include any material which will not burn or which will burn with difficulty, fibrous material being preferred. This material should also be somewhat resilient or yielding so as to form a gasket seal between the ring 17 and the horizontal surface of rabbet 11, and to this end is shown on the drawing as corrugated board, whereby the hot metal is prevented from flowing into this joint, hanging up the ingot, and producing shrinkage cracks therein.

The ring 17, regardless of whether or not it be covered at each pouring with the combined gasket and lining member 19, may be attached to the casing 12 by removable fastenings which are adapted to fail under heavy strains. This is not so essential in the form of the invention shown in Fig. 2, as in that shown in Fig. 1, but is always desirable. The means herein illustrated for securing the ring in this manner is shown and claimed in my copending application, Serial No. 511,732, filed January 28, 1931, and consists of headed pins 21 mounted with their heads down in slots 22 formed in the ring 17. The pins 21 are projected through holes drilled in the ledge 13 in 65 positions to register with the slots 22, and wedges 23 are then driven through slots in the pins 21 so positioned that the wedges may bear upon the upper surface of the ledge. When an auxiliary ledge is detached from or applied to the casing, the lining blocks or a portion of them are removed, this work being done preferably with the casing in an inverted position. Certain of the blocks are chipped away, as indicated at 24, at their lower outer edges in order to make room 75 for the wedges 23 and the upper ends of pins 21.

These fastenings are arranged at intervals throughout the perimeter of the hot top, and in the case of rectangular hot tops they are generally placed at the corners, as indicated in Fig. 3. When the auxiliary ledge member 17 is attached to the casing 12, this assembly constitutes a metallic casing. Consequently, the term "metallic casing", as hereinafter used, is to be considered as descriptive either of the casing 12 alone or of the assembly of that casing with the ring 17.

So long as a ring 17, used as disclosed in Fig. 1, remains relatively new, and particularly if its inner surface is coated with a suitable parting compound, the hot top may be stripped from the mold without any considerable difficulty. After the metal of this ring has become pitted and cracked however, due to repeated contact with molten metal, the stripping of the hot top becomes increasingly difficult. The ring should then be removed and a new one put in its place. In the event that such replacement is delayed too long, or in the event that molten metal finds its way into the joint between the ring and the rabbet 11 of the mold, welding these two parts together, it may become practically impossible to strip the ring 17 from the ingot. The force applied to pull the hot top away from the ingot will then cause the wedges 23 to cut through the metal at the upper ends of pins 21, and the casing 12 will then part from the ring 17, carrying the lining blocks 15 and 16 with it. Where the additional lining member and gasket 19 is employed however, the ring 17 will have a much greater life and there will seldom be any breaking away of the ring 17 from the casing. The member 19 35 also, of course, possesses the same advantages whether or not there is a replaceable lower ring for the casing.

Having thus described my invention, I claim:

1. In combination, a hot top adapted to rest upon the upper end of an ingot mold, said hot top comprising a metallic casing having a lower ledge for the support of lining members, a metallic member covering the lower end of the casing so as to engage the mold when the hot top is supported thereon, and means for detachably securing said metallic member to said casing.

2. In combination, a hot top casing having a lower ledge for the support of lining members, a metallic member covering the lower end of the casing having a lower surface adapted to conform with and to rest upon a trued upper surface of an ingot mold, said metallic member extending inwardly beyond the inner casing wall, and means for detachably securing said member to said casing.

3. In combination, a hot top casing having an inwardly extending ledge at the bottom thereof, a renewable metallic member covering the lower and inner surfaces of said ledge, the lower surface of said member adapted to conform with and to rest upon a trued upper surface of an ingot mold, and means for detachably securing said member to said casing.

4. In a hot top adapted to rest upon the upper end of an ingot mold, a metallic casing having a lower inwardly extending ledge, lining elements supported thereupon, and a non-metallic, non-inflammable yieldable strip covering the lower end surface of the hot top and extending upwardly for a distance over the inner surface of said lining elements, the lower portion of said strip being adapted to separate the hot top from the mold and form a seal between them.

5. In a hot top adapted to rest upon the upper

end of an ingot mold, a metallic casing having a lower inwardly extending ledge, lining elements supported thereupon, a renewable metallic member covering the lower and inner surfaces of said ledge, and a non-metallic, non-inflammable, yieldable strip covering the lower surface of said renewable member and extending upwardly for a distance over the inner surfaces of said lining elements, the lower portion of said strip being adapted to separate the hot top from the mold and form a seal between them.

6. The herein described ingot mold assembly comprising upper and lower ingot mold elements matching horizontally to form a continuous mold cavity a substantial portion of which is within the lower mold element, and a highly compressible sealing layer of cellular fibrous material combustible under temperature conditions existing during the teeming of an ingot lying horizontally between the adjacent surfaces of the lower and upper mold elements.

7. The herein described ingot mold assembly comprising upper and lower ingot mold elements matching horizontally to form a continuous mold cavity a substantial portion of which is within the lower mold element, and a compressible sealing layer of corrugated board combustible under temperature conditions existing during the teeming of an ingot lying horizontally between the adjacent surfaces of the lower and upper mold elements.

8. The herein described ingot mold assembly comprising upper and lower mold elements, the lower mold element constituting a support and closure for the upper mold element, and a compressible sealing layer of corrugated board combustible under temperature conditions existing

during the teeming of an ingot lying horizontally between the lower and upper mold elements.

9. The herein described ingot mold assembly comprising upper and lower mold elements, the lower mold element constituting a support and closure for the upper mold element, and a highly compressible sealing layer of cellular fibrous material combustible under temperature conditions existing during the teeming of an ingot lying between the adjacent surfaces of the lower and upper mold elements.

10. The herein described ingot mold assembly comprising an ingot mold divided horizontally into a plurality of ingot mold elements, and a thin sealing layer of corrugated board combustible under temperature conditions existing during the teeming of an ingot lying horizontally between adjacent faces of the mold elements.

11. The herein described ingot mold assembly comprising an ingot mold divided horizontally into a plurality of ingot mold elements, and a highly compressible sealing layer of cellular fibrous material combustible under temperature conditions existing during the teeming of an ingot lying horizontally between adjacent surfaces of the mold elements.

12. In a hot top adapted to be organized with an ingot mold, to provide a continuation of the mold cavity, which hot top includes a surface area which, in assembly with the mold lies adjacent the face of the mold, the combination of a gasket member located against said surface area, said gasket member being formed of pulpus material and being cellular in structure, so as to provide a plurality of air cells between said surface area and the adjacent face of the mold.

WALTER M. CHARMAN.
